(57) **CLAIM**

The ornamental design for a belt mounted passenger safety handle, as shown and described.

DESCRIPTION

FIG. 1 is a perspective view of my new design for a belt mounted passenger safety handle;

FIG. 2 is a top plan view thereof, the bottom plan view is a mirror image;

FIG. 3 is a right-side view of the right hand belt mounted passenger safety handle, the left hand is a mirror image and the inside view is flat with no ornamentation;

FIG. 4 is a right-side view of the right hand belt mounted passenger safety handle, dashed lines are for belt position for environmental purposes only and are not part of the design;

FIG. 5 is a front view of the right hand belt mounted passenger safety handle, the front view of the left hand handle thereof is a mirror image; and,

FIG. 6 is a rear view of the right hand belt mounted passenger safety handle, the left hand thereof is a mirror image.
